UNITED STATES PATENT OFFICE.

WILLIAM M. FAWCETT AND CHARLES L. HEISLER, OF ERIE, PENNSYLVANIA,
ASSIGNORS TO JULIAN SCHOLL AND COMPANY, OF NEW YORK, N. Y.

ROAD-ROLLER.

SPECIFICATION forming part of Letters Patent No. 728,451, dated May 19, 1903.

Application filed January 6, 1903. Serial No. 138,033. (No model.)

To all whom it may concern:

Be it known that we, WILLIAM M. FAWCETT and CHARLES L. HEISLER, citizens of the United States, residing at Erie, in the county 5 of Erie and State of Pennsylvania, have invented certain new and useful Improvements in Road-Rollers, of which the following is a specification.

This invention relates to improvements in 10 power-operated road-rollers, and particularly to the steering mechanism and connections between the steering-roller and said mechanism and frame.

The details of our improvements will be 15 made plain in the following specification, taken in connection with the accompanying drawings, in which—

Figure 1 is a side elevation of the machine. Fig. 2 is a central longitudinal section taken 20 vertically through the forward part of the machine. Fig. 3 is a front view of the machine with the rollers removed. Fig. 4 is a plan view, partly in section, on the line 5 5 of Fig. 2. Fig. 5 is a side view of the swivel-pin by 25 means of which the steering mechanism is connected to the yoke. Fig. 6 is a sectional view taken transversely through the yoke at the swivel-pin. Fig. 7 is a bottom plan view of the forward part of the machine. Fig. 7^a 30 is a modification, and Fig. 8 is a view showing in detail the gearing for applying the power of the engine to the steering mechanism.

Referring to the drawings, A indicates the main frame of the machine, the walls of which 35 form the water-tank, and B indicates an upright boiler, which is suitably supported within the main frame. The lower wall 1 of the main frame curves upwardly and forwardly over the steering-roller C, and the side walls 40 2 and 3 converge toward the end, as shown in Figs. 3 and 4, the forward end of the tank or frame thus forming a gooseneck, which extends above the steering-roller. A bearing-block 4 is arranged at the forward end of the 45 gooseneck between the lower wall 1 and the upper wall 5, and within this block is journaled a horizontal king-post 6, having a flattened head 7, which projects beyond the end of the gooseneck and extends into a recess 8 50 in the center of a vertical yoke 9, in the ends of which the roller C is journaled. The yoke

is detachably connected to the horizontal king-post by a coupling-pin 10, which extends through a vertical opening in the yoke and the head 7 of the king-post. The horizontal 55 king-post therefore supports the weight of the forward end of the frame and permits the yoke and roller to rock transversely with respect to the frame, while the coupling-pin connects the yoke to the king-post and permits the yoke 60 and roller to turn about a vertical axis for the purpose of steering. Roller or ball bearings 11 may be arranged between the yoke and the head of the king-post. The connection of the yoke to the frame by a horizontally-projecting king-post permits the use 65 of a steering-roller of large diameter without increasing the height of the machine. On account of the height of the yoke-connecting devices above the ground and the lever- 70 age which obstructions upon the ground would exert upon the yoke the coupling devices would be strained or broken unless they were made very heavy or some provision was made for taking up the thrust upon the roller, and 75 thus relieving the shock and pressure upon the coupling devices. In order to take up the horizontal thrust and transmit it directly to the frame instead of through the coupling devices, we connect an auxiliary yoke to the 80 lower end of the main yoke, the auxiliary yoke extending around the rear face of the roller and having an arcuate slot concentric with the vertical axis of the yoke, and a thrust-pin secured to the lower side of the frame extends 85 into this slot and prevents forward or backward movement of the roller relatively to the coupling devices and frame. As shown in the drawings, the auxiliary yoke comprises the side bars 12 and 13, which are secured to the 90 lower ends of the main yoke below the axle of the roller by bolts 14 and brace-rods 15^a and a pair of flat bars 15 and 16, secured to the rear ends of the side bars and extending around the rear of the roller, the bars 15 and 95 16 being separated from one another and their adjacent edges being concentric throughout the greater portion of their length with the vertical axis upon which the roller turns in steering. An arcuate guide-slot 17 is thus 100 formed in the auxiliary yoke between the guide-bars 15 and 16. As shown, the bars 15

and 16 are connected at their ends by tie-plates 16^a, secured to the lower sides of the bars, and the tie-plates and said bars are bolted securely to the side bars 12 and 13. A bearing block or plate 18 is secured to the bottom of the tank at the forward end thereof and centrally located between its sides, and a strap or yoke 19, also attached to the lower wall of the tank, extends beneath said bearing-plate. A thrust pin or stud 20 extends through an opening in the strap 19 and into an opening in the plate 18 and is secured in position by a nut 21, which is threaded to the stud and clamps the strap 19 between the nut 15 and a shoulder 22 upon the stud. The main portion of the stud projects below the strap and carries a roller 23, which fits into the slot 17, the roller being of such diameter that very little side play is allowed between the roller 20 and the edge of the slot. The upper end of the stud 20 extends into an opening in the bearing-plate 18, so that the stud is supported at two points against the thrust of the yoke. It will be seen that in every position 25 into which the roller is moved for the purpose of steering the thrust-pin will prevent rearward and forward movement of the roller relatively to the coupling devices and frame, and the coupling devices will not be strained 30 by obstructions encountered by the roller.

Upon the upper wall 5 of the frame or tank and at the forward end thereof is arranged a gear-casing 24, having bearings 25 and 26, within which is journaled a vertical steering 35 shaft or head 27. The upper end of the casing has an enlargement 28, within which is arranged a worm-gear segment 29, secured to the shaft 27 and engaging a worm 30 upon a worm-shaft 31, which worm-shaft is suitably 40 journaled in the sides of the casing and is provided with hand-wheels 32. An opening 33 is formed in the side of the gear-casing at its lower end, and a steering-lever 34, secured to the steering-shaft 27, projects laterally 45 through this opening. Upon the outer end of the steering-lever is arranged a sleeve 35, which is free to turn upon the lever, and a link 36 is pivotally secured to said sleeve and projects forward through an eye in a swivel- 50 pin 37, which is journaled in vertical openings in the horizontal portion of the main yoke of the roller and at one side of its vertical axis. Strong compression-springs 38 and 39 are arranged upon the link at opposite 55 sides of the head of the swivel-pin, these springs being compressed against the head of the pin by means of adjusting-nuts 40 and 41, respectively. The form and arrangement of the swivel-pin are illustrated in Figs. 5 and 6. 60 In these figures it will be noted that the eye 42 of the pin is beveled at its upper and lower edges, as indicated by the numeral 43, so that the link may have a vertical rocking motion within the eye. The pin, as shown, is secured to the yoke by means of a washer 44 and cotter-pin 45.

In the operation of the steering-gear the

movement of the worm-segment by the worm 70 swings the steering-lever in the desired direction, and the latter through the link, compression-springs, and swivel-pin transmits the motion to the steering-yoke. On account of the sleeved connection between the link and the lever and also on account of the bevel 75 form of the eye in the swivel-pin and the yielding connection between the link and pin the roller may oscillate about the horizontal king-post without straining any of said parts. The universal connection between the link and the steering-lever and the swiveling of 80 the vertical pin 37 permits the angular relations between the lever, link, and yoke to change without straining any part. The main purpose of the springs between the swivel-post and the link is to afford a yielding connection between the yoke and the steering mechanism, which will prevent the transmission of severe and sudden shocks to the worm-gearing. It will be seen that any obstruction tending to turn the roller from its course 90 will compress one spring or the other, according to the direction in which the machine is moving, and thus the steering mechanism will be protected against damaging shocks. This is desirable, for the reason that where 95 worm-gearing is used to steer the machine the gearing itself cannot yield when an obstruction is encountered.

In addition to the means for operating the steering mechanism by hand-power previously described provision is also made for operating said mechanism by motor-power, this power being applied to the worm-shaft 31. In the drawings the steering mechanism is operatively connected with the engine D, 100 which propels the road-roller. Referring to Figs. 1 and 8, 46 in the latter figure represents one end of the engine-shaft, which projects into a casing 47. Secured to the shaft within the casing is a beveled driving-pinion 105 48. A shaft 49, which transmits power to the steering mechanism, extends through the casing 47 at right angles to the engine-shaft 46, and upon said shaft 49 are arranged two beveled gears 50 and 51, which turn loosely upon 110 the shaft and mesh with the driving-pinion 48. Obviously the gears 50 and 51 will turn in opposite directions when the engine is in motion. In the opposite side of the casing from the driving-pinion is arranged an idle 115 wheel 52 without teeth, which bears against the rims of the gears 50 and 51 to counteract any side thrust which may be given to the gears 50 and 51 by the driving-pinion. The idler is journaled upon a fixed stud 53, which 120 is suitably secured to the casing. The gears 50 and 51 are provided with shells or sleeves 54 and 55, which project toward one another, these shells being preferably formed integral 125 with the gears and having their inner faces tapering or conical, as shown. Each shell has a leather lining 56, which forms a friction-surface. Upon the shaft 49 and between the gears 50 and 51 is secured a double-

coned drum 57 of such diameter that it will not engage the friction-surfaces of either of the sleeves upon the gears when the drum is in the central position, (shown in Fig. 8;) but when moved slightly in either direction from the central position it will engage one or the other of the friction-surfaces. As the gears 50 and 51 are constantly rotated in opposite directions when the engine is in motion, the shaft 49, upon which it is secured, may be turned in either direction by moving the drum into engagement with the proper friction-surface. The shaft 49 extends forwardly into a gear-casing 58 at the end of the worm-shaft 31. Upon the end of the worm-shaft 31 within the gear-casing is secured a beveled gear 59, (see Fig. 8;) which is engaged by a pinion 60 upon the shaft 49. This pinion has a long hub 61, through which the shaft 49 extends. The shaft is movable longitudinally within the hub, and the pinion is caused to turn with the shaft by means of a spline or key 62. The power-transmitting shaft 49 may thus be moved longitudinally in order to engage or disengage the drum and friction-surfaces without disturbing the relation of the gears 59 and 60. This longitudinal movement of the shaft 49 is accomplished by means of a link 63, suitably connected at one end to a hand controlling-lever 64 and having at its opposite end a fork 65, which is connected to a trunnion-collar 66, loosely mounted upon the shaft between a pair of collars 67 and 68, which are secured to the shaft. It will be evident that by moving the controlling-lever 64 backward or forward from its mid-position the worm-shaft 31 will be turned by the power of the engine, resulting in turning the steering-roller about its vertical axis. When the steering-roller is turned to the desired angle, the controlling-lever is brought to the central position, and the worm-gearing will hold the roller at the same angle until power is again applied to the worm-shaft. It will be noticed that when the controlling-lever is in its central position the worm-wheel may be turned by hand-power for the purpose of steering, there being no interference between the motor mechanism and the hand appliances.

Instead of providing two curved guide-bars on the auxiliary yoke with a single thrust pin or stud between said bars we may, as shown in Fig. 7^a, use only a single guide-bar 16^b and arrange studs 20^a and 20^b at the opposite edges of the bar.

Having described our invention, what we claim, and desire to secure by Letters Patent, is—

60 1. In a self-propelled road-roller, the combination with a frame and a steering-roller, of a main yoke extending over the roller and movable about a vertical axis, an auxiliary yoke connected to the main yoke and extending around the rear face of the roller, said auxiliary yoke having an arcuate slot concentric with the vertical axis of the main

yoke and a stud secured to the frame and extending into said slot.

2. In a self-propelled road-roller, the combination with a frame and a steering-roller, 70 of a main yoke extending over the roller and movable about a vertical axis, an auxiliary yoke connected to the main yoke and extending around the rear face of the roller, said 75 auxiliary yoke having an arcuate slot concentric with the vertical axis of the main yoke, a stud secured to the main frame and extending into said slot, and a roller upon said stud. 80

3. In a self-propelled road-roller, the combination with a frame having a gooseneck and a king-post journaled in the gooseneck and projecting horizontally therefrom, of a steering-roller, a main yoke extending over said 85 roller and pivotally connected to the king-post, an auxiliary yoke connected to the main yoke and extending around the rear face of the roller and having an arcuate slot concentric with the vertical axis of the main yoke, 90 and a stud secured to the frame and extending into said slot.

4. In a self-propelled road-roller, the combination with a frame having a gooseneck and a king-post journaled in the gooseneck and 95 projecting horizontally therefrom, of a steering-roller, a main yoke extending over said roller and pivotally connected to the king-post, an auxiliary yoke connected to the main yoke and extending around the rear face of the roller and having an arcuate slot concentric with the vertical axis of the main yoke, 100 a stud secured to the frame and extending into said slot and a roller upon said stud.

5. In a self-propelled road-roller, a main 105 frame, a steering-roller, a yoke extending over the steering-roller and pivotally connected to the main frame, a steering-lever for turning said yoke and roller about a vertical axis, a link connecting said lever with the yoke at one side of the vertical axis, and a spring connection between said link and yoke.

6. In a self-propelled road-roller, a main frame, a steering-roller, a yoke extending over the steering-roller and pivotally connected to the main frame, a steering-lever for turning said yoke and roller about a vertical axis, 115 a link connecting said lever with the yoke at one side of the vertical axis, and a spring connection between said link and yoke. 120

7. In a self-propelled road-roller, a main frame, a steering-roller, a yoke extending over the steering-roller and pivotally connected to the main frame, a steering-lever for turning 125 said yoke and roller about a vertical axis, a link having a universal connection with the lever and extending through an eye upon the yoke, stops upon said link, and springs interposed between said stops and eye. 130

8. In a self-propelled road-roller, a main frame, a steering-roller, a yoke extending over the steering-roller and pivotally connected to the main frame, a steering-lever for turning

said yoke and roller about a vertical axis, and a link having a universal connection with the lever and a spring connection with the yoke.

9. In a self-propelled road-roller, a main frame, a steering-roller, a yoke extending over the steering-roller and pivotally connected to the main frame, a steering-lever for turning said yoke and roller about a vertical axis, a swivel-pin journaled in the yoke at one side 5 of the vertical axis, and a link connecting said lever with the swivel-pin.

10. In a self-propelled road-roller, a main frame, a steering-roller, a yoke extending over the steering-roller and pivotally connected to the main frame, a steering-lever for turning 15 said yoke and roller about a vertical axis, a swivel-pin journaled in the yoke at one side of the vertical axis, said swivel-pin having an eye, a link having a universal connection 20 with the lever and extending through the eye of the swivel-pin, stops on said link and springs interposed between said stops and the swivel-pin.

11. In a self-propelled road-roller, a main frame, a steering-roller, a yoke extending over the steering-roller and pivotally connected to the main frame, a steering-lever for turning said yoke and roller about a vertical axis, worm-gearing for operating said lever, a 25 swivel-pin journaled in the yoke at one side of the vertical axis, said swivel-pin having an eye, a link having a universal connection with the lever and extending through the eye of the swivel-pin, stops on said link and 30 springs interposed between said stops and the swivel-pin.

12. In a self-propelled road-roller, the combination with a main frame having a gooseneck, a king-post journaled in the gooseneck 40 and projecting horizontally therefrom a steering-roller, and a yoke extending over said roller in front of the gooseneck and pivoted to the king-post, of a vertical steering-shaft supported upon the frame, worm-gearing for 45 operating the shaft, a steering-lever secured to said shaft, a swivel-pin journaled in the yoke at one side of its vertical axis, said swivel-pin having an eye, a link extending through said eye and having a universal connection 50 with the steering-lever, stops upon said link and springs interposed between said stops and pin.

13. In a self-propelled road-roller, the combination with a steering-roller, a worm-shaft 55 and intermediate mechanism for turning said roller about a vertical axis, of a motor, friction-surfaces rotatable in opposite directions, by said motor, a transmitting-shaft geared to said worm-shaft, a friction wheel or drum secured to said transmitting-shaft, and means for moving said transmitting-shaft longitudinally comprising a hand-lever, a link operatively connected to said lever, said link having a forked end, and a trunnion-collar journaled upon the shaft and connected to the 60 forked end of the link.

14. In a self-propelled road-roller, the com-

bination with a steering-roller, a worm-shaft and intermediate mechanism for turning said steering-roller about a vertical axis, of a motor, conical frictional surfaces rotatable in opposite directions by said motor, a transmitting-shaft geared to worm-shaft, a double-coned drum upon said transmitting-shaft, and means for moving said shaft and drum longitudinally.

15. In a self-propelled road-roller, the combination with a steering-roller, a worm-shaft and intermediate mechanism for turning said steering-roller about a vertical axis, of a motor, a beveled pinion upon the motor-shaft, a pair of beveled gears opposed to one another and meshing with said pinion, said gears having sleeves or shells projecting from their adjacent faces and provided with conical friction-surfaces, a longitudinally-movable transmitting-shaft, a double-coned friction-drum upon said shaft between said gears, gearing connecting said transmitting-shaft with the worm-shaft, and means for moving said transmitting-shaft longitudinally.

16. In a self-propelled road-roller, the combination with a steering-roller, worm-shaft and intermediate mechanism for turning said steering-roller about a vertical axis, of a motor, a beveled pinion upon the motor-shaft, a pair of beveled gears opposed to one another and meshing with said pinion, said gears having sleeves or shells projecting from their adjacent faces and provided with conical friction-surfaces, a transmitting-shaft upon which said friction-gears are journaled, a double-coned drum upon said shaft between the friction-gears, a gear upon the worm-shaft, a pinion upon the transmitting-shaft 105 meshing with said gear, said transmitting-shaft being movable longitudinally through said latter pinion and the friction-gears, and hand-operated means for moving said transmitting-shaft longitudinally.

17. In a self-propelled road-roller, the combination with a main frame having a gooseneck, and a king-post journaled horizontally in the gooseneck, of a steering-roller, a main yoke extending over said roller and pivotally connected to the king-post, an auxiliary yoke connected to the main yoke and extending around the rear face of the roller concentric with the vertical axis of the main yoke and means connected with the frame for taking up the horizontal thrust of said auxiliary yoke.

18. In a self-propelled road-roller, the combination with a main frame having a gooseneck and a king-post horizontally arranged therein, of a steering-roller, a yoke extending over the roller and connected to said king-post, said yoke being movable about a vertical axis, an auxiliary yoke extending around the rear face of the roller below the horizontal axis of the roller and concentric with the vertical axis of the main frame, and means connected with the main frame for taking up the horizontal thrust of said auxiliary yoke.

19. In a self-propelled road-roller, the combination with a main frame having a goose-neck and a king-post horizontally arranged therein, of a steering-roller, a main yoke extending over the roller and connected to said king-post, said yoke being movable about a vertical axis, an auxiliary yoke extending around the rear face of the roller, and a device for taking up the horizontal thrust of said auxiliary yoke, said device being secured to

the main frame in fixed relation thereto in the rear of the roller and engaging parts upon the yoke at the rear of the roller.

In testimony whereof we affix our signatures in presence of two witnesses.

WILLIAM M. FAWCETT.
CHARLES L. HEISLER.
